Primary Examiner — Michelle E. Wilson*Assistant Examiner* — Sanjeev Paul(74) *Attorney, Agent, or Firm* — Reilly Intellectual Property Law Firm(57) **CLAIM**

The ornamental design for a sound amplification device, as shown and described.

DESCRIPTION

FIG. 1 is a front perspective view showing my new design; FIG. 2 is a top view of FIG. 1;

FIG. 3 is a front view of FIG. 1;

FIG. 4 is right side view of FIG. 1;

FIG. 5 is a left side view of FIG. 1; and,

FIG. 6 is a bottom view of FIG. 1.

The broken lines are included for the purpose of illustrating environmental structure and form no part of the claimed designs used in FIGS. 1 through 6.

1 Claim, 4 Drawing Sheets(56)
